DESIGN FOR A HOOD OR SIMILAR ARTICLE

Leon Fainblatt, New York, N. Y.

Application June 1, 1939, Serial No. 85,287

Term of patent 3½ years

To all whom it may concern:

Be it known that I, Leon Fainblatt, a citizen of the United States of America, residing in New York city, in the Borough of Manhattan, county and State of New York, have invented a new, original, and ornamental Design for a Hood or Similar Article, of which the following is a specification, reference being had to the accompanying drawing, forming part thereof, wherein

The characteristic feature of my design resides in the combination on the specific hood disclosed of the specific, contrastingly colored, marginal flaps and tie portion embroidered as shown.

I claim:

The ornamental design for a hood or similar article, substantially as shown and described.
